UNITED STATES PATENT OFFICE.

WILLIAM L. HURLEY, OF SVENSEN, OREGON.

DRAG-SAW MECHANISM.

1,110,789.

Specification of Letters Patent. Patented Sept. 15, 1914.

Application filed August 27, 1913. Serial No. 786,948.

To all whom it may concern:

Be it known that I, WILLIAM L. HURLEY, a citizen of the United States, residing at Svensen, in the county of Clatsop and State of Oregon, have invented a new and useful Drag-Saw Mechanism, of which the following is a specification.

The present invention appertains to drag saws, and relates more particularly to a mechanism for actuating the drag saw.

It is the object of the present invention to provide a novel and improved apparatus for actuating a common cross cut saw, for severing or cutting logs or the like.

Another object of the present invention is to provide novel means for guiding the cross cut saw, whereby the saw will be prevented from buckling or flexing.

A further object of the present invention is to provide novel means for spring pressing the saw in order that it may yieldingly engage the log, or within the kerf or slot cut in the log.

With the foregoing general objects outlined and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawings, wherein—

Figure 1 is a side elevation of the apparatus, part of the saw being broken off, and a portion of the steam engine being shown in longitudinal section. Fig. 2 is a plan view of the parts depicted in Fig. 1. Fig. 3 is an enlarged fragmental detail of the cross head, saw guide, and saw spring. Fig. 4 is a cross section of the parts illustrated in Fig. 3, the section being taken on the line 4—4 of Fig. 3. Fig. 5 is a side elevation of the valve lever.

In carrying out the present invention, there is employed an elongated fluid pressure cylinder 1, having the depending clamp 2 intermediate its ends, for supporting the cylinder, as will be apparent, and having the upstanding steam chest 3 inclosing the sliding valve 4. The valve 4 is of the usual

type, and controls the steam passages extending from the steam chest 3 to the end portions of the cylinder 1, as usual. The usual piston head 6 works within the cylinder 1 and has a relatively long stroke, the piston rod 7 extending from the head 6 through the head 8 attached to the forward or outer end of the cylinder 1. The head 8 carries an upstanding bracket 9 through which the outer or free end of the valve stem 5 is guided. The valve gear is carried by an upstanding arm or bracket 10 carried by the forward head 8 of the cylinder, and includes a lever 11 fulcrumed to the arm or support 10, a link 12 connecting the lower arm of the lever 11 and the intermediate portion of the valve stem 5, whereby the rocking motion of the lever 11 will impart a reciprocatory or rectilinear motion to the valve stem. The link 12 is connected to the valve stem 5 by means of a suitable clamp 12'. The upper arm of the lever 11 is equipped with a pair of spaced ears or lugs 13 carrying the stop screws 14, a lever 15 also being fulcrumed to the support 10 and having a block or projection 16 extending from one side and working between the ears 13 of the lever 11. Thus when the actuating lever 15 is swung to the ends of its strokes, the block 16 in contacting with the respective stop screws 14, will throw the valve lever 11 properly, so as to slide the valve 4 to reverse the inlet of steam or other fluid pressure into the cylinder 1, as is well understood in the art.

The saw guide embodies a pair of bars 17 attached to the head 8 of the cylinder or body 1 of the machine and projecting longitudinally from the cylinder, or parallel with the axis of the cylinder, the forward or free ends of the bars 17 being connected by a yoke 18 of inverted U-shape. The bars 17 are spaced only slightly apart, so as to receive a common cross cut saw therebetween.

A cross head 19 is attached to the forward or outer end of the piston rod 7 to move along the upper edges of the guide bars 17, and has a forwardly projecting fork embodying the arms 20 disposed slidably upon the upper edges of the guide bars 17. The cross cut saw 21 is disposed snugly between the guide bars 17 under the yoke 18 and has its rear or inner end fitting within the arms 20 of the cross head fork, and fulcrumed therebetween by means of a pivot pin or rivet 22 passed through the ends of the arms

20 and through the saw. It is evident that the bars 17 will not only serve to guide the saw, but will also serve to guide the cross head carrying the saw.

5 Shoes 23 are carried by the arms 20 and slidably engage the lower edges of the guide bars 17, the shoes being carried by the straps or webs 24 depending from the fork arms and slidably engaging the remote sides of 10 the guide bars. It is evident that the shoes 23 working underneath the saw guide, will properly guide the cross head for reciprocation along the saw guide.

One of the arms 20 is provided with an 15 upstanding arm or extension 25 to which one end of a link 26 is pivoted, the other end of the link 26 being pivoted to the upper or free end of the actuating lever 15, whereby the actuating lever 15 will be oscillated as 20 the cross head is reciprocated with the piston rod.

As a means for yieldingly depressing the saw, a lever 27 is positioned over the upper or inactive edge of the saw at the inner or 25 rear of the saw, and is provided with a fork or angular bifurcated portion 28 straddling the rear upper corner of the saw, and fulcrumed thereto by means of a pin or rivet 29. The free or forward end of the lever 27 30 is provided with an angular or depending bifurcated portion or fork 30 engaging over the upper edge of the saw, to lock the lever 27 against lateral or sidewise movement. The lever 27 carries a jam screw 31 adjoining its free end, or adjoining the angular portion 30, engaging the edge of the saw, and the jam screw 31 engages the upper edge of the saw for the purposes which will 35 hereinafter appear. A leaf spring 32 is secured upon the lever 27 and has its free end resting upon the cross head 19, the leaf spring 32 tending to depress the saw, and the tension of the spring being regulated by the jam screw 31.

40 In operation, the apparatus is supported in any suitable manner, by means of the clamp 2, in order that the saw 21 may engage a log or other object to be cut as is well understood in the art. Then, as the 45 steam or fluid pressure is admitted into the steam chest 3, the same will be directed to the proper end of the cylinder 1. Supposing the apparatus to be started with the parts arranged as illustrated in Fig. 1, the piston rod will first be forced forwardly or outwardly so as to carry the saw forwardly over the log, and at the same time, the lever 15 will be swung forwardly 50 through the medium of the link 26 connected to the cross head. After the piston rod has reached the forward end of its stroke, the block 16 will have engaged the forward stop screw 14, so as to swing the valve lever 11 in such a direction as to reverse the position of the slide valve 4, whereby the pis-

ton 6 will be forced rearwardly. The piston being forced rearwardly will cause the saw 21 to be dragged back over the log, and as the piston rod reaches the end of its rearward stroke the lever 15 will again throw 70 or swing the valve lever 11 to correspondingly throw the slide valve 4 for changing the course of the steam, as is obvious. Thus, as the above operation is continued, the saw will be alternately pushed and 75 dragged over the log. Upon the outward or forward movement of the saw, the same is adapted to yield so as to clear the saw dust in the slot of the log cut by the saw, and during the return or drag movement of the 80 saw, the same will work its way into and through the log.

From the foregoing, taken in connection with the drawings, the advantages incident to the present structure will be apparent to those familiar with the art, particular attention being directed to the fact that the present apparatus is so designed that it will permit of the employment of a common cross cut saw without the liability of the 90 saw buckling or flexing under the fluid pressure.

The present apparatus is a light and portable one, and carries out the objects aimed at in a satisfactory manner. 95

Having thus described the invention, what is claimed as new is:

1. In a device of the character described, a guide, a cross head working upon the guide, a saw fulcrumed to the cross head and working within the guide, and a leaf spring coöperating with the upper edge of the saw and the top of the cross head for yieldingly depressing the saw. 100

2. In a device of the character described, a guide, a cross head working therealong, a saw fulcrumed to the cross head and working within the guide, an adjustable member mounted upon the inactive edge of the saw and a leaf spring carried by the said member and having its free end engaging the cross head to yieldingly depress the saw. 105

3. In a device of the character described, a guide, a cross head working therealong, a saw fulcrumed to the cross head and working within the guide, a lever fulcrumed to the saw, a leaf spring attached to the lever and having its free end engaging the cross head, and means carried by the lever and engaging the saw for swinging the lever against the tension of the spring. 110

4. In a device of the character described, a guide, a cross head working therealong, a saw fulcrumed to the cross head and working within the guide, a lever having a bifurcated portion at one end straddling the inactive edge of the saw and fulcrumed to the saw and having a bifurcated portion at its free end straddling the said edge of the saw, 115

a leaf spring secured to the lever and having its free end engaging the cross head, and a jam screw carried by the lever and engaging the said edge of the saw.

5 5. In a device of the character described, a body, a pair of parallel guide bars carried thereby and projecting therefrom, a reciprocating member carried by the body and having a cross head movable along the upper 10 edges of the guide bars, the cross head having a fork whose arms are slidable upon the upper edges of the guide bars, the fork arms having depending webs slidably engaging the remote sides of the guide bars, and the

webs having shoes engaging the lower edges 15 of the guide bars, a yoke connecting the free ends of the guide bars, and a saw disposed snugly between the guide bars and having one end pivoted between the said fork arms.

20 In testimony that I claim the foregoing as my own, I have hereto affixed my signature in the presence of two witnesses.

WILLIAM L. HURLEY.
